C. C. HISCOE.

WALL AND CEILING COVERING.

No. 19,604.

Patented Jan. 21, 1890

UNITED STATES PATENT OFFICE.

CHARLES CONSTANTINE HISCOE, OF NEW YORK, N. Y., ASSIGNOR TO
FREDERICK BECK, OF SAME PLACE.

DESIGN FOR A WALL AND CEILING COVERING.

SPECIFICATION forming part of Design No. 19,604, dated January 21, 1890.

Application filed December 26, 1889. Serial No. 335,034. Term of patent 3½ years.

To all whom it may concern:

Be it known that I, CHARLES CONSTANTINE HISCOE, a citizen of Great Britain, residing at New York, in the county of New York and State of New York, have invented and produced a new and original Design for a Wall and Ceiling Covering, of which the following is a specification, reference being had to the accompanying drawing, forming part there-
10 of.

The leading feature of my design consists of a number of scrolls of different sizes, figure 1, having a beaded edge on one side and a plain edge on the other side. These scrolls
15 are placed at irregular distances and revolve in different directions. In the intervening

spaces are placed rivet-heads, figure 2, and also circular buttons, figure 3, of different sizes. The groundwork, figure 4, of the design is filled in with a crepe-like pattern. 20

What I claim is—

The design for a wall and ceiling covering herein shown and described, consisting of beaded scrolls of different sizes placed at irregular distances, and circular buttons and rivet-heads, with a groundwork of crepe-like pattern. 25

CHARLES CONSTANTINE HISCOE.
